UNITED STATES PATENT OFFICE.

RALPH R. RICHARDSON, OF CHICAGO, ILLINOIS, ASSIGNOR TO CHICAGO CARTON COMPANY, OF CHICAGO, ILLINOIS, A CORPORATION OF ILLINOIS.

FOLDABLE BOX.

1,182,585.

Specification of Letters Patent.

Patented May 9, 1916.

Application filed December 20, 1915. Serial No. 67,717.

To all whom it may concern:

Be it known that I, RALPH R. RICHARDSON, a citizen of the United States, and a resident of Chicago, in the county of Cook and State of Illinois, have invented certain new and useful Improvements in Foldable Boxes; and I do hereby declare that the following is a full, clear, and exact description thereof, reference being had to the accompanying drawings, and to the reference characters marked thereon, which form a part of this specification.

This invention relates to foldable boxes, and more particularly to that type of such boxes which are set up or formed from flat blanks made from sheet material, such as paper-board, fiber-board, or the like.

Among the objects of my invention is to improve the construction of boxes of the kind referred to, and to provide in particular a foldable box made from relatively stiff and rigid paper or fiber-board, and which box may be effectively used as a shipping container for articles of wearing apparel, such as pairs of shoes and the like.

A further object of my invention is to so improve the construction of the box that, when set up or formed from the flat blank, the walls of the box will be held rigidly in place and be prevented from displacement by the weight or shifting of the articles packed therein, as well as being collapsed by the exterior strains to which the box is subjected in rough handling and during transportation of the same.

The invention also relates to the blank from which my box is formed.

The invention consists further in the matters hereinafter described and more particularly pointed out in the appended claims.

In the accompanying drawings: Figure 1 is a plan view of a cut and scored blank from which a box embodying the features of my invention is formed; Fig. 2 is a perspective view of the box set up from the blank shown in Fig. 1; Fig. 3 is a transverse sectional view taken on line 3—3 of Fig. 2; Fig. 4 is a sectional view taken on line 4—4 of Fig. 3; and Figs. 5 and 6 are sectional views taken on lines 5—5 and 6—6, respectively, of Fig. 4.

Referring to the drawings, illustrating in detail one preferred form of foldable box embodying the features of my invention, 10, in Fig. 1, indicates in flat form a cut and

scored blank from which my box is formed. Said blank 10 is preferably made from a sheet of relatively stiff and rigid sheet material, such as fiber-board, paper-board, or the like. As shown in Fig. 1, said blank 10 is substantially rectilinear in form, and is divided transversely by a plurality of parallel score or fold lines 11, 12, and 13 into four connected, substantially similar sections 14, 15, 16, and 17, the latter constituting, in the order named, the top wall or lid or cover of the box and the rear, bottom, and front walls thereof, when the box is set up for use. The intermediate section 15 is provided at each end thereof with an integral end extension 18, 18, the latter being in length equal to the combined width of the connected sections 14, 15, and 16. The end portions 11^a, 12^a of the score or fold lines 11, 12 are continued through each end extension 18, 18, and divide the same into three connected flaps 19, 20, and 21. The intermediate flap 20 is divided from the section 15 by a score or fold line 22, 22, the latter being arranged substantially at right angles to and intersecting said score or fold lines 11, 12. The flaps 19, 21 are each equal in length to the width of the sections 14, 16, to which they are oppositely disposed, and said flaps 19, 21 are separated from said sections 14, 16 by slits or lines of severance 23, 24, the inner ends of which terminate in said score or fold lines 11, 12, as shown in Fig. 1. The end section 17 is provided at each end thereof with an end extension 25 forming a flap 25, 25, the latter being divided from said section 17 by a score or fold line 26, 26. Said fold lines 26, 26 are parallel to each other and arranged substantially at right angles to and intersecting the fold line 13. Said end flaps 25, 25 are each equal in length to the width of the opposed flaps 21, 21, and are divided therefrom by slits or lines of severance 27, 27 in alignment with the score line 13 and extending at their inner ends into said slits 24, 24. The opposite end section 14 is provided with an integral extension forming a flap 28, which is divided from said section by a score or fold line 29. As illustrated, the base of said flap 28 has the same length as the section 14 to which it is joined, and the side edges of said flap 28 converge toward each other, so as to give a tapered form thereto. The free end of said tapered flap 28 is provided

with an integral locking member or head 30 adapted to be folded into a position at substantially right angles thereto on a score or fold line 31, which is arranged at the base 5 of said locking tongue and divides the same from said tapered flap 28. Said locking head 30 is preferably made in the form shown in Fig. 1, and is provided with a neck 32 narrower than the extreme width of 10 said head, there being locking shoulders 33, 33 on each side of said neck. The section 16 is provided intermediate its ends and along the fold line 13 with a locking slot or notch 34 adapted to receive said locking tongue or 15 head 30, when the box is set up and in use. Each end flap 20, 20 is provided within its margin with an arc-shaped locking tongue 35, 35 adapted to be inserted into a locking notch or slot 36, 36 formed in said end flap 20 25, 25, when said box is set up.

In Fig. 3, the box is indicated by 37, and the same is set up from the flat blank 10 shown in Fig. 1 in substantially the following manner. The sections 15, 16, and 17 are 25 folded on said score or fold lines 12 and 13 in the proper manner and order so that the section 16 will form the bottom wall of the box; the section 15, one side or the rear wall of the box; and the section 17, the other side 30 or front wall of the box. When the parts are then folded, the section 14 extends above the side or rear wall 15 and in a position to be swung downward on the fold line 11 to form the top wall or lid or cover for said 35 box. The end flaps 20, 20 on the rear wall 15 are swung inward on the score or fold lines 22, 22 into positions extending between said front and rear walls 15, 17 and closing the ends of the box. The other end flaps 25, 40 25 at the ends of the front wall 17 are swung inward into positions extending between said front and rear walls and being overlapped by said outermost end flaps 20, 20. The end edge 38, 38 of each end flap 25 45 abuts throughout its length against the inner face of the rear wall 15, as shown in Figs. 5 and 6. The flaps 20, 25 at the ends of the box being overlapped, the box is provided in effect with double end walls. In 50 folding said end flaps 20, 20 into the positions referred to, the upper and lower flaps 19, 21, respectively, of said end flaps 20 are folded toward each other on the score or fold lines 11^a, 12^a so as to extend into the box from the upper and lower margins of 55 said outermost end flaps 20, 20. The lower flap 21 extends into the box beneath the lower edge 39 of the associated innermost end flap 25, 25, and said lower edge 39 60 bears downward on said lower flap, as shown in Fig. 4. Said lower flaps 21, 21 overlap the bottom wall 16, as shown in Figs. 4 and 6, and have their inner free end edges 40, 40 abutting. Said lower flaps 21, 65 21 extend between the front and rear walls

of the box and have their lateral or side edges 41, 41 abutting against the inner faces of said walls. The upper flaps 19, 19 extend into the box over the upper edges 42 of said innermost end flaps 25, 25, and the 70 inner ends of said flaps overlap each other, as shown in Figs. 4 and 6. The upper edges 42, 42 of said innermost end flaps 25, 25 bear upward against the under sides of said upper flaps 19, 19, as shown in Fig. 4. As 75 shown in Fig. 6, said upper flaps 19, 19 extend between the front and rear walls of the box, and the side edges 43, 43 of said upper flaps abut against the inner faces of said walls. After the parts are in the positions above referred to, the cover or lid 14 is swung downward upon and over the upper flaps 19, 19. The tapered flap 28 is folded on its score or fold line 29 into a position overlapping the outer or exterior 80 face of the front wall 17, and the locking head or tongue 30 on said tapered flap is bent into a position substantially at right angles to the said front wall 17 and inserted into and through the locking slot 34 85 at the base of said front wall. As illustrated in Fig. 3, said locking head 30 extends into the box and lies between the bottom wall 16 and the lower, inwardly extending flaps 21, 21. Said locking slot 34 90 being in length less than the extreme width of said locking head 30, the shoulders 33, 33 on the latter extend beyond the ends of said slot and prevent the locking head from being easily withdrawn therefrom. Before 95 the lid or cover 14 is closed and locked in position, the overlapping end flaps 20, 25 are secured or locked together by inserting the arc-shaped locking tongues 35 into and through the locking slots 36, 36. (See Figs. 100 1 and 4.)

The foldable box 37 herein described and shown is particularly designed for use in shipping or transporting articles of wearing apparel, such as a pair of shoes or the like, 105 although it is to be of course understood that said box may be used for any purpose desired, and I do not wish to restrict the box to the character of service referred to, nor to transporting the specific articles of wearing apparel mentioned, as other articles may be 110 packed in the box. Said box 37 being made of relatively stiff material, such as fiber-board, paper-board, or the like, insures that the walls of the box possess the desired degree of rigidity and strength as to support 115 (without bending or bulging) the article or articles packed therein, as well as be strong enough to withstand the usual strains exerted on the box in rough handling and during transportation of the same. Inasmuch as the end edges 38, 38 of the innermost end flaps 25, 25 abut against the inner surface of the rear wall 15, and the side edges 41, 43 of the upper and lower flaps 19, 21, respec- 120 125 130

- tively, bear against the inner surfaces of the front and rear walls of the box, said parts serve to rigidly hold and space apart the front and rear box walls, and, further, tend 5 to brace and prevent said walls from being collapsed or displaced inward, when an inwardly directed pressure is applied against the outside of the box. Inasmuch as the end edges 40, 40 of the lower flaps 21, 21 meet 10 and abut, said flaps serve to hold the end flaps or walls 20, 25 in their properly spaced positions, and act to prevent said end walls from being collapsed inward in the rough handling of the packed box during ship- 15 ment. When the box 37 is closed, the lid or cover 14 overlaps and holds the upper, inwardly extending flaps 19, 19 in their positions extending between and abutting against said front and rear walls. The fact 20 that the locking tongue or head 30 engages and extends substantially at right angles to the front wall 17, insures rigid locking of the cover 14 in its closed position, and holds the cover from movement in either direction 25 during the transportation of the packed box. By reason of the arrangement of the locking head 30, the cover 14, when locked in its closed position, is prevented from being opened by an upward pull thereon.
- 30 A box made as above described and shown, in addition to being light in weight, is rigid and braced throughout, and is well adapted as a shipping container for the articles referred to, because of the fact that, 35 when the box is packed and locked, the parts will hold their positions during transportation.
- Although I have shown and described herein in detail one preferred form of fold- 40 able box embodying the features of my invention, yet it is to be understood that the details of construction and arrangement of parts illustrated may be variously changed and modified without departing from the 45 spirit and scope of my invention, and I do not wish to be limited and confined to the exact details of construction and arrangement of parts shown, except as pointed out in the annexed claims.
- 50 I claim as my invention:
1. A foldable box, comprising connected top, bottom, front, and rear walls, each of said front and rear walls being provided with end flaps adapted to overlap each other 55 and form the end walls of said box, the outermost of each of the overlapping end flaps being provided at its upper and lower margins with inwardly extending flaps, the latter extending across the edges of associated innermost end flaps and having their 60 lateral edges abutting against said front and rear walls, and said top wall having hinged connection with said rear wall and being provided with a foldable flap adapted to overlap said front wall, when the top wall is 65 closed, and said foldable flap being provided with a locking tongue adapted to be folded into a position substantially at right angles to said front wall and be inserted into said box through a locking slot formed in said 70 front wall adjacent said bottom wall.
2. A blank for a foldable box made from a sheet of sheet material, and divided transversely by a plurality of parallel score or fold lines into four connected sections forming the top, bottom, front and rear walls of the box, the section forming the rear wall of the box being provided with integral extensions on each end thereof, each end extension being divided by score or fold lines into 75 three connected flaps, the intermediate one forming the end wall of the box when set up, and the other two flaps being divided from the blank by slits or lines of severance and extending into the box from the upper 80 and lower edges of said intermediate flaps, the section forming the front wall being provided with integral end extensions divided from the blank by slits or lines of severance and being overlapped by the end 85 flaps on the rear wall when said box is set up, and the section forming the top wall or cover of the box being provided with an integral extension forming a foldable flap 90 adapted to overlap the front wall when the 95 box is set up and the cover is closed, and said last named flap being provided with a locking head or tongue adapted to be bent into a position substantially at right angles to said flap and be inserted in a locking slot formed 100 in said front wall on the score or fold line dividing said sections forming the front and bottom walls of the box.

In testimony that I claim the foregoing as my invention I affix my signature in the 105 presence of two witnesses, this 8th day of December, A. D. 1915.

RALPH R. RICHARDSON.
